CELLAR-DRAINING PUMP

Abraham Pollak, Linfield, Pa.

Application September 1, 1945, Serial No. 614,050

3 Claims. (Cl. 103—87)

1

This invention relates to improvements in cellar-draining pumps.

Pumps of this character are used in connection with suitable sumps. It is desirable that the maximum proportion of the water collected in the sump be removed, and heretofore, cellar-draining pumps have been made of a large number of pieces or parts; conventional inlet-openings have been provided with strainers and positioned in the bottom of the pump beneath the pump-casing, and impellers having vanes extending downwardly have had bearings on the pump casing on opposite sides of the impeller. The liquid in a sump usually contains a percentage of solid or foreign material that sometimes clogs the strainer and inlet-opening and in a pump of the bottom-inlet type hereinabove referred to, the inlet opening, when clogged, is inaccessible and foreign matter cannot be removed without dismantling the piping or without lifting the pump out of its normal position, and, furthermore, in said bottom-inlet type of pump, operation of the impeller tends to stir up and prevent precipitation of solid matter to the bottom of the sump.

In accordance with my invention, I provide a highly-efficient pump made of relatively few parts, that will have an inlet in the surface of its impeller-housing so that the liquid supply will be taken from a sump-strata above the bottom and will not stir up or prevent precipitation of solid matter; that will not only be much simpler, stronger and more durable than the multi-pieced prior-art pumps but also, because of its relatively thin flat body, will keep the liquid in the sump at a low level while enabling the immersing of the pump body in the liquid of the sump and the positioning of a screened pump-inlet at the top of the pump casing, where it is less likely to become clogged than in other constructions and where, in the event of clogging, is, without any dismantling of the piping, easily accessible for the removal of foreign matter.

Another feature of my invention is the provision in a cellar-draining pump of a pump body provided with an impeller comprising a disc having vanes extending upwardly, and a single shaft connected only with the upper surface of said disc and extending upwardly therefrom.

Another feature of my invention comprises the provision in a cellar-draining pump of a pump-body made from a single metal-casting and including a casing having a volute portion, supporting legs extending radially from the pump-casing, and an upwardly-extending axial por-

2

tion comprising a bearing for the impeller shaft and a housing for inlet openings.

Another feature of my invention is the utilizing of an impeller mounting at the top surface only in which a lower bearing that cannot be lubricated by conventional means is eliminated, and the substitution of bearings so positioned at the top of the pump body as to be readily accessible and capable of lubrication by a single conventional grease reservoir connected to a lubricating channel positioned above the pump-casing adjacent to the inlet.

Still another feature of my invention is the utilizing, in combination with an integral upwardly-extending axial portion at the top of the pump-body, including an inlet-housing having inlet-openings, of a screen member for encircling the inlet housing and means for fastening the screen thereto.

With these and other objects in view, the invention comprises the combination of members and arrangement of parts so combined as to coact and cooperate with each other in the performance of the functions and the accomplishment of the results herein contemplated, and comprises in one of its adaptations the species or preferred form illustrated in the accompanying drawings, in which—

Fig. 1 is a view in side elevation of a cellar-draining pump embodying my invention;

Fig. 2 is a view in front elevation of the pump shown in Fig. 1;

Fig. 3 is a transverse section on the line 3—3 of Fig. 1;

Fig. 4 is a transverse sectional view on the line 4—4 of Fig. 1;

Fig. 5 is a vertical section substantially on the line 5—5 of Fig. 2;

Fig. 6 is a plan view of the bottom of the pump with the closure-plate for the impeller-housing removed;

Figs. 7 and 8 are top and face views of the switch mechanism, and its attaching and supporting means; and

Figs. 9 and 10 are complemental illustrative views of the switch and the operating-arm therefor.

Referring now to these drawings which illustrate a preferred embodiment of my invention, I indicates a pump which, in the embodiment shown, comprises a pump-casing 2, composed of a hollow body in which the top and side casing walls, the volute portion 3, the feet 4 and the bottom rim 2^a are formed in one piece. The hollow-body of the casing 2 has an open bottom to

provide an impeller-insertion opening 5 at said bottom and a closure cover 5^a is provided for hermetically sealing the said insertion opening when the impeller is inserted and properly mounted in the casing 2, a gasket or sealing ring 5^b being inserted between the rim 2^a and said closure cover 5^a.

In accordance with the preferred form of my invention, the pump casing 2 has at an axial position above said casing a cylindrical integral portion or member 6 comprising a combined inlet housing 6^a and an impeller-bearing block 7 having a bearing bore 7^a which is readily accessible and adapted to be easily lubricated by a suitable grease reservoir 8 communicating with said bearing bore 7^a through a grease-bore 8^a in said block.

In the embodiment shown, the said integral axial portion 6 is also provided with a tapped socket 9 for the reception and fastening of the threaded lower end of a shaft-enclosing column 10, which also has a motor-supporting function.

An impeller 11 is inserted through the opening 5 and is enclosed within the casing. The said impeller 11 is also preferably cast in a single piece embodying an impeller disc 11^a, vanes 11^b extending upwardly therefrom and an axial hub 11^c also extending upwardly therefrom. A shaft 12 is mounted in the lubricated bearing bore 7^a hereinabove referred to and has its lower end extending within and connected to said hub 11^c. As shown, I connect the impeller hub and shaft by tapping the hub 11^c and threading the end of the shaft 12 to engage said tapped hub 11^c. The column 10, thus connected to the integral axially disposed cylindrical portion 6, extends upwardly a suitable distance and encloses the impeller shaft 12, to the upper end of which shaft a suitable motor 13 is operatively connected. As illustrated, the disc of the impeller 11 is provided with a series of perforations 11^d as shown in Fig. 6, and as the bottom surface 11^a of the impeller 11 is spaced, as shown in Fig. 5, from the closure cover 5^a, these perforations permit liquid to pass through the impeller and to provide liquid on opposite sides thereof.

Electric motors used in horizontal position on various household appliances are conventional and relatively inexpensive, and I preferably adapt one of such motors for use in vertical position in my cellar-draining pump. This is accomplished by removing one of the conventional resilient mounting rings at one end of the motor and utilizing the annular supporting flange of such mounting in vertical position as a means of locating and supporting the motor in axial registration with the impeller-shaft 12 and column 10.

As illustrated, the motor-shaft 13^a and the upper end of the impeller shaft 12 are connected together by a coupling element 14 and the shell or housing 13^b of the motor and its shaft 13^a are axially-supported on the top of the column 10 by providing at the upper end of the column an adapter sleeve 10^a having at its upper end a split mounting member 10^b which engages a stationary annular motor-mounting flange 13^c on the motor shell or housing 13^b. The adaptor-sleeve 10^a is provided with a suitable opening 10^c to provide a suitable frame and support for the motor switch and its mounting and operating means herein-after specified.

Suitable means is provided for automatically actuating the motor upon the filling with liquid of the sump and, for this purpose, a conventional switch 15 for the motor is mounted on the column

10 in position to be actuated by actuating means hereinafter specified. As illustrated, the switch 15 is fitted in a switch-supporting casing 15^a fitted into the adaptor-sleeve opening 10^c and fastened to the column by bracket-wings 15^b. The switch has a conventional operating lever-arm 16, and I provide therefor an actuating fork 17 pivoted at 17^c to the opposite sides of the switch casing 15^a and connected to said conventional switch lever-arm 16 by the provision in the fork 17 of a socket 17^a into which the outer end of the switch lever-arm is seated. I now provide automatic means for swinging this fork 17 about its pivots to throw the switch into operative and inoperative positions, respectively, for the purpose of starting and stopping the motor.

My preferred means for so operating the switch 15 comprises a vertical operating rod 18 passing through an aperture 17^b in the fork 17 and suitably arranged between stop members 18^a—18^b on the rod 18. The rod is slidably mounted intermediate its ends at the outer bored end of a projecting supporting arm 18^a integral with a ring 19, fastened on the column 10. The rod 18 has at its lower end a float 20 which extends into the liquid in the sump and through its buoyancy will move the mounting rod 18 upwardly and the lower member of the stops 18^a—18^b at its upper end will raise the fork 17 to throw the switch 15 when such water rises in the sump to a predetermined level. Reversely, when the pump has reduced the water in the sump to a suitable level, the upper stop member 18^a will engage the fork 17 to move the switch arm in the opposite direction to stop the motor. An adjustable movement-limiting stop 18^c is fastened on the rod 18 above the supporting arm 18^a to position the float and prevent excessive downward movement of the switch-actuating rod 18 and float 20.

In the preferred embodiment of my invention I provide a closure or cover which hermetically seals the bottom of the casing which is relatively thin or shallow in depth so that liquid in the sump will overflow the top of the casing in order to enter the dual inlet-openings which are screened by a cylindrical screen 21 which surrounds the integral inlet housing 6^a and is fastened in place preferably by the grease reservoir 8.

In the embodiment shown I provide a cap or hood member 22 for the upper end of the motor, which also comprises the upper end of my cellar-draining pump. This cap is provided with a central circular opening which fits over and engages a conventional mounting ring 23 which is conventionally found on motors and is usually composed of resilient material. The cap will thus be securely held in place on this motor mounting element.

The operation of the device will be substantially obvious from the above description. It will be seen, however, that applicant's pump body or pump casing will be completely immersed in the liquid of the sump; that the feet will rest on the bottom of the sump and that because of the shallow depth of the pump-casing the inlet of the pump will be low enough to reach liquid relatively close to the bottom of the sump; that this construction, therefore, will not stir up mud or other foreign matter but will take relatively clear liquid. Furthermore, if the inlet of the pump becomes clogged it will be readily accessible for cleansing by the user without the dismantling of the outlet piping or other parts of the installation.

It will be seen from the above that I have provided an extremely simple, highly durable pump

construction which, because of the inclusion in a single casting of the volute, the pump-casing with its axial member having an inlet housing, bearing block and column socket, as well as the integral feet or supporting elements, will enable manufacture of the device at an economical cost and will provide structural characteristics that will have much greater and durable qualities than similar devices heretofore manufactured, and also is of such simple construction and operation that once installed will remain in proper operation and will not get out of order or be easily broken.

My improved construction furthermore enables the parts which are likely to get out of order to be readily demounted so as to enable renewal thereof. The accessibility of the single bearing of the impeller shaft for ready lubrication (which cannot be accomplished in constructions in which the inlet aperture is at the bottom of the pump casing) also promotes facile fully-lubricated operation of the pump.

Having described my invention, I claim:

1. A cellar-draining pump embodying, in combination, an impeller having a flat upper face provided with vanes, an impeller shaft, a pump-casing forming a primary bearing-support for said impeller-shaft and having an integral annular inlet-housing portion provided with side openings above said impeller face for the admission to the casing of water, a primary shaft-bearing in said annular housing comprising an impeller-shaft bearing-block portion extending diametrically across and vertically therethrough in opposition to said side openings and provided with an impeller-shaft-bore disposed at a right angle to the upper face of the impeller, said block having at its upper end a thrust-bearing surface, a collar on said shaft having a bearing against said thrust-bearing surface, said inlet housing portion also being provided with a column-mounting socket disposed concentrically with said shaft bore, a cylindrical shaft-enclosing column supported in said socket, a single auxiliary bearing-support disposed at the upper end of said column, a motor provided with a shaft-bearing supported on said auxiliary support and having a drive shaft extending concentrically of said impeller shaft, and a coupling element connecting said impeller and motor shafts together.

2. A cellar-draining pump embodying, in combination, a pump casing embodying a relatively wide and shallow impeller housing having an open bottom and partially enclosed by outer and top walls formed respectively of a short perimetric

rim flange and a wide, flat and horizontally-positioned ring-like portion having an axial opening, said pump-casing also including a relatively slender inlet-housing disposed centrally above said axial opening in said flat ring-like horizontally - positioned portion and communicating through said axial opening with the impeller housing, said inlet housing having side water-inlet openings positioned over said shallow impeller housing and at a low position on the pump, said inlet housing also being provided with a shaft-supporting bearing-block extending diametrically across said inlet housing in the path of admitted water, said bearing block being provided with an axial bore, an impeller comprising a substantially flat disc mounted in said impeller housing and having shallow vanes, an impeller shaft having its lower end connected to said impeller disc at the axis thereof and extending through the axial bore in said bearing block, a motor connected with said impeller shaft for rotating said impeller in said shallow housing, and a flat closure plate for the open bottom of said impeller housing.

25 3. A cellar draining pump as claimed in claim 2 in which a volute section is provided in the top wall of the impeller housing between said rim-flange and the flat ring-like wall portion of said impeller housing, and pump-supporting feet are provided which project radially from the perimetric rim flange in a horizontal plane substantially registering with the bottom edge of said rim flange to increase the area of support of the pump while maintaining the shallowness of the impeller housing and the lowness of the inlet openings over the same.
